United States Patent Office.

ASA C. BROWNELL, OF BROOKLYN, NEW YORK.

Letters Patent No. 103,293, dated May 24, 1870.

IMPROVEMENT IN COMBINATION BATH-TUBS.

The Schedule referred to in these Letters Patent and making part of the same.

To all whom it may concern:

Be it known that I, ASA C. BROWNELL, of Brooklyn, in the county of Kings and State of New York, have invented a new and useful Improvement in Combination Bath-Tub; and I do hereby declare that the following is a full, clear, and exact description thereof, which will enable others skilled in the art to make and use the same, reference being had to the accompanying drawings forming part of this specification.

This invention relates to bath-tubs, and consists in an improved construction thereof, which will be specified hereinafter.

In the accompanying drawing—

Figure 1 represents a vertical longitudinal section of a combination bath-tub constructed according to my invention.

Figure 2 is a top or plan view.

Similar letters of reference indicate corresponding parts.

A is the bath-tub, which, in form and construction, does not necessarily differ from bathing-tubs of ordinary construction.

B is the sitz bathing-tub, which is simply a hollow half cylinder, of metal or of any suitable material, connected with the sides of the tub A, placed transversely across the foot of the tub, as seen in the drawings.

The hollow semi-cylinder may be made with ends, so as to form a water-tight vessel of itself, and be so constructed otherwise as to be supported in the foot of the bath-tub by means of sockets or lugs, or from the top of the tub or by cleats on the sides of the tub, as may be found most convenient, so that they may be readily detached, but I prefer to permanently at-

tach them to the tub, as represented in the drawing.

The front edge of the sitz tub is rolled, as seen at C, so as to form a convenient rest for the body.

D represents a tap-hole through the bottom of the sitz tub. The water is discharged into the main tub through the sitz tub.

E is the overflow-pipe, and

F the discharge-pipe.

In filling the tub B for a sitz bath, the hole D is, of course, closed, and, in fact, it may be kept closed except when the water is to be discharged from it, as the front edge is dropped down, below the top of the main tub, so that the water will flow over it. This sitz tub does not interfere with the use of the common bath-tub, and it may be readily attached thereto, either removably or otherwise.

It is apparent that clean water (either hot or cold) may be retained in sitz bath-tub ready for use in any desired manner, either during or after the ordinary bath.

The advantages of this arrangement are many, and must be obvious to all.

Having thus described my invention,

I claim as new, and desire to secure by Letters Patent—

As an improved article of manufacture, a bath-tub, A, having the half cylinder B rigidly fixed across the foot thereof, and extending down about half the depth of the tub, thus forming a compound sitz and plunge-bath, as set forth.

A. C. BROWNELL.
